Inventor:

FRANÇOIS RICHARD

Curt B. Mueller.

UNITED STATES PATENT OFFICE.

FRANÇOIS RICHARD, OF CLEVELAND, OHIO.

DESIGN FOR AN AUTOMOBILE-RADIATOR.

57,726.

Specification for Design.

Patented Apr. 26, 1921.

Application filed July 24, 1920. Serial No. 398,817. Term of patent 7 years.

To all whom it may concern:

Be it known that I, FRANÇOIS RICHARD, a citizen of the French Republic, residing at 7800 Finney Ave., Cleveland, in the county of Cuyahoga and State of Ohio, have invented a new, original, and ornamental Design for an Automobile-Radiator, of which the following is a specification, reference being had to the accompanying drawing, forming part thereof.

The figure is a front elevation of an automobile radiator embodying my invention.

I claim:

The ornamental design for an automobile radiator as shown.

FRANÇOIS RICHARD.
